UNITED STATES PATENT OFFICE.

HOWARD H. BAKER, OF BUFFALO, NEW YORK.

PHONOGRAPH-NEEDLE HOLDER.

Application filed October 16, 1922. Serial No. 594,935.

This invention relates to a holder or mounting for the needles of phonographs and has for its object the provision of a needle holder which not only reproduces sounds from the records unaccompanied by the usual scratchy noises but also brings out the full sweetness, values and shading of the tones in striking resemblance to the original vocal, instrumental or other tone renditions.

This invention has the further object to so construct the needle holder that the same may be easily and conveniently adjusted while the phonograph is in operation to render the selection either loud or soft or any desired intermediate volume of tone as best suits the character of the selection or the conditions under which the phonograph is operating and thus permits of dispensing with the mufflers, dampers or sound controllers now commonly employed in connection with such instruments.

In the accompanying drawings:

Figure 1 is a fragmentary perspective view of a phonograph equipped with my improved needle holder. Figure 2 is a longitudinal section of the same. Figure 3 is a bottom plan view of the same. Figure 4 is an inner end view thereof. Figure 5 is a cross section on line 5—5, Fig. 2. Figure 6 is an outer end elevation thereof, showing the heavier part of the needle support arranged above the needle for producing a loud rendition of the record. Figure 7 is a similar view, showing the heavier part of the needle holder arranged on one side of the center of the needle for producing a soft rendition of the selection. Figure 8 is a fragmentary longitudinal section of the core taken on line 8—8, Fig. 2. Figure 9 is a similar longitudinal section taken at right angles to Fig. 8 and omitting the needle and clamping screw. Figure 10 is a perspective view of the clamping screw. Figure 11 is a longitudinal section similar to Fig. 2, showing a modified form of my invention. Figure 12 is a bottom plan view of the same.

Similar characters of reference indicate corresponding parts throughout the several views.

The sound box 20 shown in Fig. 1 is one form now commonly employed on phonographs and suitable for use in connection with my invention, the same being mounted on the usual tone arm 21 and provided on

its underside with a socket 22 in which a phonograph needle is ordinarily secured by means of a set screw 23, so that its pointed lower end can trace the grooves in the record, which in the present form is shown as a disk 24 rotatably mounted immediately below the sound box.

Instead of securing the needle 25 directly to the socket on the sound box, the same is secured indirectly thereto by means of the holder embodying my invention and yielding the advantages above enumerated. This holder in the form shown in Figs. 1-10 is constructed as follows:

As a whole, the holder forms a support for the needle which is heavier on one side of the needle than on the other which serves to modify the tone produced in a manner as will presently appear.

In the preferred construction, the support comprises an inner metallic member or core 26 which carries the needle and outer metallic member or shell 27 arranged around the core and mounted on the sound box, and a cushion 28 interposed between the core and shell, this support being elongated and having the axis of its elongation arranged at right angles to the axis of the needle mounted thereon and the sound box socket 22 with which it is connected. The core and shell by preference consists of brass although other metals having the requisite resonance may be employed, and the cushion consists of rubber or other elastic material which has the capacity of transmitting tone vibrations but eliminating therefrom sharp scratchy effects due to imperfections in the record. For convenience and ease of manufacture, the core and shell are made generally of cylindrical form and the cushion is likewise made of this form and arranged between the same for a sufficient longitudinal distance to insure a proper support for the needle. The shell preferably has the form of a tube which is open at one end and closed at the other end by a head 29 which is formed integral therewith and extends across the corresponding end of the core. The open end of the shell is provided with a peripheral enlargement 30 in which is secured a rearwardly projecting shank 31 which is inserted in the socket 22 of the needle arm and fastened therein by the set screw 23.

The exposed outer end of the core which corresponds to the open end of the shell car-

ries the needle while the inner end of the same is separated from the adjacent head of the shell by an intervening space 32, thereby avoiding metallic contact between these members and preventing the transmission of harsh sounds from the needle to the sound box but instead compelling all sound vibrations to be transmitted through the cushioning member which has the effect of absorbing 5 the scratch vibrations of the record and permitting the passage of those vibrations only to have true tone value or quality and thus rendering the selection more faithfully and agreeably. For the purpose of increasing 10 the mellowness and resonance of the tones thus transmitted, the inner end of the core facing the head of the shell is bored out to form a longitudinal cavity 33 extending to the exterior of the core at its inner 15 end, as shown in Fig. 2.

Various means may be employed for detachably fastening the needle to the outer end of the core, those shown in Figs. 2, 3, 8, 9 and 10 being preferred and consisting 20 of a socket 34 extending transversely through the outer end portion of the core and receiving the butt end of the needle so that the pointed end of the latter projects forwardly therefrom and a clamping screw 35 working 25 in an internally threaded opening 36 formed axially or lengthwise in the outer end of the core and bearing at its inner end against the side of the shank of the needle. This screw is able to thus engage the needle without deflecting the latter by reason of the opening 36 being bored sufficiently deep so that its inner end terminates at or intersects the center of the needle socket, thereby supporting the end portions of the needle butt 30 around its entire circumference while one side of the central part of the butt is supported on the intermediate semi-circular portion of the socket and the opposite side of the intermediate portion of the needle butt is engaged by the clamping screw 35. In order to prevent the pressure of this screw from bearing with its central part on the butt of the needle and thus possibly 35 tilting or cocking the same at an angle, in the event of any imperfections in workmanship, the central part of the inner end of this screw is provided with a recess 37 which produces an annular rim 38 on this end of the screw 35. By this means this screw can 40 only bear at widely separated points against the needle butt upon engaging the same, which points are arranged adjacent to the extremities of the needle socket and thus ensure a grip on the needle over a wider area and causing the same to be held reliably in its proper position in the core. For 45 convenience in turning the screw 35 the outer end of the same is provided with a knurled thumb piece 39.

60 In the preferred construction, the needle

25 and the attaching shank 31 are arranged on diametrically opposite sides of the holder and axially in line with each other, as shown, or nearly so, which arrangement is possible by cutting away a part of the 70 side wall of the shell adjacent to its open end, as shown at 40, for the passage of the needle into and out of the socket in the core.

If desired, the needle may be secured to 75 the core in the manner shown in Figs. 11 and 12, in which case the outer end of the core is provided with a transverse socket 41 which is triangular in cross section and adapted to receive either round or triangular needles which are held in said socket by a clamping screw 42 arranged on the core.

Owing to this construction of the needle holder and the manner of mounting the 80 same on the sound box, the preponderating weight of the support for the needle on one side of the same, due to arranging the needle and shank on the outer end and open end of the core and shell, respectively, it 85 is possible to shift this weight so that it 90 presses the point of the needle with varying effect against the undulating surfaces of the grooves on the record. Accordingly, if the needle holder is turned about the axes 95 of the needle and shank so that the heavier inner end and the headed end of the core and shell are arranged vertically or directly above the needle, as shown by full lines in Figs. 1 and 6, the latter will be pressed 100 against the undulating surfaces of the record with a maximum force and thereby obtain the loudest volume of tone from the record. If, however, the heavier end of the 105 holder is turned about the axes of the needle and shank so that the same is arranged horizontally or projects laterally from one side of the needle, as shown by dotted lines in Fig. 1 and by full lines in Fig. 7, then the needle is pressed with a minimum force 110 against the undulating surfaces of the record which results in producing the softest rendition of the record. Similarly the preponderating weighted end of the holder body may be turned about the axes of the 115 needle and shank so as to occupy an angular position intermediate the extreme vertical and horizontal positions just described and thus cause a corresponding intermediate volume of tone to be delivered from the 120 record.

It is thus possible by adjusting this overhanging weight of the holder to so adjust the same to suit the particular selection which is rendered, the size of the room in which the phonograph is operating and other conditions. This adjustment in the volume of the tone is effected without adjusting the needle lengthwise for this purpose as is commonly done to either shorten 125 or lengthen the unsupported front or pointed 130

end of the needle nor does it require the size of the needle to be changed to obtain different tone effects.

In all of the various positions of the holder, no change is effected in the purity or quality of the tone as compared with the natural tone but instead the tone retains its purity and clearness regardless of whether the reproduction is loud or soft.

10 This holder therefore renders it possible to dispense with the usual mechanical devices now commonly found in phonographs for accomplishing this purpose and thereby materially reduces the cost of the same without sacrificing quality or purity, but instead improving the quality as to resonance, mellowness and richness of tone and the eliminating of stray vibrations so that the finest shades of tones are reproduced and 20 a tone quality is obtained which is sweet and true to nature.

I claim as my invention:

1. A phonograph needle holder comprising a support having attaching means for 25 attaching a needle thereto, and connecting means for connecting the same with a sound box, said support being heavier on one side of the axis of the needle than the other said attaching means and connecting means being 30 axially in line and said support being capable of rotary adjustment about the means which connect the same with the sound box as an axis.

2. A phonograph needle holder comprising 35 a support provided on opposite sides with means for fastening a needle to the support and with means for fastening the support to a sound box, and said support being heavier on one side than the other of a line connecting said means for fastening the needle to the support and the means for fastening the latter to the sound box and said support being capable of rotary adjustment about the means which connect the same with the 40 sound box as an axis.

3. A phonograph needle holder comprising 45 a support provided on one side with a socket in which a needle is to be fastened and on its diametrically opposite side with a shank adapted to be fastened to a sound box, said support being heavier on one side than the other of a line connecting said socket and shank said socket and shank being in line and said support being capable 50 of rotary adjustment about the means which connect the same with the sound box as an axis.

4. A phonograph needle holder comprising a metal core adapted to carry the needle, a

metal shell arranged around the core and 60 adapted to be attached to a sound box, and a cushion interposed between said core and shell, an air space being formed between parts of said core and shell.

5. A phonograph needle holder comprising 65 a metal core adapted to carry the needle, a metal shell arranged around the core and adapted to be attached to a sound box, and a cushion interposed between said core and shell, said core and shell having a greater 70 part of their bodies arranged on one side of the needle than on the other.

6. A phonograph needle holder comprising 75 a metal core adapted to carry the needle, a metal shell arranged around the core and adapted to be attached to a sound box, and a cushion interposed between said core and shell, said core and shell having a greater 80 part of their bodies arranged on one side of the needle than on the other and constructed to form an air space at those ends of said bodies which are farthest from the needle.

7. A phonograph needle holder comprising 85 a cylindrical core provided at one end with a transverse socket adapted to receive a needle and having a longitudinal cavity in its other end extending to the exterior of the core at the corresponding end, a shell enclosing said core and adapted to be attached to a sound box, and a cushion interposed between said core and shell. 90

8. A phonograph needle holder comprising 95 a cylindrical core provided at one end with a transverse socket adapted to receive a needle, a cylindrical shell arranged around the core and having a head which extends across that end of the core opposite to the one containing said socket, a cushion arranged between said core and shell, that end of the shell opposite to the one having the head being cut away on its front side to expose the front end of said socket in the core. 100

9. A phonograph needle holder comprising 105 a cylindrical core provided at one end with a transverse socket adapted to receive a needle, a cylindrical shell arranged around the core and having a head which extends across that end of the core opposite to the one containing said socket, a cushion arranged between said core and shell, that end of the shell opposite to the one having the head being cut away on its front side to expose the front end of said socket in the core, and a shank arranged externally on the shell 110 opposite to its cut away portion and substantially in diametrical alignment with said needle socket. 115
